COMBINED WELL COVER AND TROUGH

Filed Oct. 26, 1928

UNITED STATES PATENT OFFICE.

ALEXANDER J. CORMIER, OF TYLERTOWN, MISSISSIPPI.

COMBINED WELL COVER AND TROUGH.

Application filed October 26, 1928. Serial No. 315,257.

This invention is a device to be placed over the top of bored well curbing for the purpose of keeping objects from falling into the well or being thrown into the same, and also for 5 the purpose of keeping the well mouth and its surroundings dry and sanitary.

Further, it is an object to provide a combined well cover and trough in which that portion which serves as the mounting means 10 for the trough proper also functions as a cap with cover for the well mouth.

Further, it is an object to provide the trough proper with a covered or guarded remote end, such end having an outlet in the 15 bottom for the discharge of the water, the cover, however, terminating short of the well bucket to be lowered into the trough.

Again, it is an object of the invention to provide the trough with means to effect an 20 automatic opening of the outlet valve of the bucket upon its being set into the trough thereby to release the water into the trough.

Another object is to provide a supporting cap with a hinged cover, the flange of which 25 is adapted to rest on the upper edges of the sides of the trough proper whereby to hold the cover out of contact but close to the upper edge of the cap so as to provide for air circulation beneath the cap, if desired.

30 Other objects will in part be obvious and in part be pointed out hereinafter.

To the attainment of the aforesaid objects and ends, my invention resides in the novel features of construction, combination and arrangement of parts, all of which will be first 35 fully described in the following detailed description, then be partially pointed out in the appended claims, reference being had to the accompanying drawing, in which:

40 Figure 1 is a perspective view of a well top with my invention applied, the lid being open.

Figure 2 is a central vertical longitudinal section, the lid being closed and a well bucket being indicated in the trough in dotted lines.

45 In the drawing, in which like numerals indicate like parts in all of the figures, 1 represents the well curbing over the top of which the supporting cap 2 of my apparatus fits. The cap 2 has an inwardly projecting flange 3 to which is hinged the cover 4 the front flange 5 of which is adapted to rest on the upper edges of the sides 9 of the trough proper when the cap is down while the side flanges 6 of the cover embrace the adjacent 50 sides of the cap 2.

The trough proper consists of a bottom 7 and sides 9 the latter extending partly across the sides of the cap 2 and being riveted or otherwise secured to the cap. The bottom 7 is bent up at 8 and fits on the inside of the cap 60 between it and the well curbing 1, the upwardly bent portion 8 being riveted or otherwise secured to the cap, as may be desired.

It is to be noted that the upper edges of the sides 9 adjacent the cap 2 are located below 65 the upper plane of the cap, the purpose for this will be clear later.

The trough proper has an outlet slot 10 in its bottom wall adjacent that end which is remote from the well, the portion cut from the 70 bottom 7 to make the opening 10, being downwardly bent to form a pouring lip 11.

In order to keep the water from splashing out and over on the ground below so as to avoid wetting the ground around the well 75 the remote end of the trough proper is enclosed by a cover 12 which extends over the front and a portion of the top of the trough proper, the cover 12 having side flanges 13 riveted or otherwise secured to the sides 9. 80 It also has an abutment flange 14 projecting beneath the forward edge of the bottom 7 and being riveted or otherwise secured thereto as may be desired.

15 are braces which are pivoted at 16 to the 85 trough proper and at their other ends are suitably secured to the well curbing 1.

Within the trough proper is a member 17 which is secured to the bottom 7 in any suitable way in alignment with the space between 90 the cover 12 and the cap 2. It is into this space that the bucket of water from the well is set. These buckets are usually provided with valves in their bottom and when the bucket is set over the member 17 that member 95 engages the valve to push it open thus effecting an automatic discharge of the water from the bucket into the trough.

The cover 12 may be provided with corner notches or indentations 18 in order to hold 100 the bail of a bucket into which it is desired to have the water discharge. If it is desired to get the water in a bucket which has a bail the bail can be hooked over the end of the trough and held in the notches 18 against 105 slipping off while being filled.

From the foregoing description taken in connection with the accompanying drawing, it is thought the construction, operation and advantages of my invention will be readily 110

apparent to those skilled in the art to which it relates.

What I claim is:

1. A device of the character described comprising a tubular supporting cap to fit over the upper end of a well curbing, a trough proper carried by said cap, said trough proper comprising a body having a discharge opening in its bottom wall adjacent the end remote from the cap, and a cover over said remote end.
2. A device of the character described comprising a tubular supporting cap to fit over the upper end of a well curbing, a trough proper carried by said cap, said trough proper comprising a body having a discharge opening in its bottom wall adjacent the end remote from the cap, a cover over said remote end, said cover constituting an end wall for the trough proper and extending over the top of said trough proper, there being a space at the top of said trough proper between said cap and said cover to admit of the lowering of a well bucket into the trough.
3. A device of the character described comprising a tubular supporting cap to fit over the upper end of a well curbing, a trough proper carried by said cap, said trough proper comprising a body having a discharge opening in its bottom wall adjacent the end remote from the cap, a cover over said remote end, said cover constituting an end wall for the trough proper and extending over the top of said trough proper, there being a space at the top of said trough proper between said cap and said cover to admit of the lowering of a well bucket into the trough, and means in said trough proper in register with said space to engage the outlet valve of a well bucket located within the trough and open the same.

4. A device of the character described comprising a tubular supporting cap to fit over the upper end of a well curbing, a trough proper carried by said cap, said trough proper comprising a body having a discharge opening in its bottom wall adjacent the end remote from the cap, a cover over said remote end, said cover constituting an end wall for the trough proper and extending over the top of said trough proper, there being a space at the top of said trough proper between said cap and said cover to admit of the lowering of a well bucket into the trough, means in said trough proper in register with said space to engage the outlet valve of a well bucket located within the trough and open the same, and a cover over said cap.

5. A device of the character described comprising a tubular supporting cap to fit over the upper end of a well curbing, a trough proper carried by said cap, said trough proper comprising a body having a discharge opening in its bottom wall adjacent the end remote from the cap, a cover over said remote end, and a flanged cover hinged to said cap, said trough proper having side walls extending from said cap and spaced below the top of said cap and said cover having one of its flanges to rest on said side walls when the cover is down.

6. A device of the character described comprising a tubular supporting cap to fit over the upper end of a well curbing, a trough proper carried by said cap, said trough proper comprising a body having a discharge opening in its bottom wall adjacent the end remote from the cap, a cover over said remote end, and braces extending from said trough proper to the well curbing.

ALEXANDER J. CORMIER.
